UNITED STATES PATENT OFFICE.

HARRY M. ABERNETHY, OF CLEVELAND, OHIO, ASSIGNOR TO THE AMERICAN RAILWAY SIGNAL COMPANY, OF CLEVELAND, OHIO, A CORPORATION OF OHIO.

AUTOMATIC RAILWAY BLOCK-SIGNAL.

No. 829,309.

Specification of Letters Patent.

Patented Aug. 21, 1906.

Application filed January 25, 1906. Serial No. 297,889.

To all whom it may concern:

Be it known that I, HARRY M. ABERNETHY, a citizen of the United States, residing at Cleveland, in the county of Cuyahoga and State of Ohio, have invented new and useful Improvements in Automatic Railway Block-Signals, of which the following is a specification.

This invention relates to improvements in electrically-operated signal systems for railway purposes wherein a semaphore-arm is actuated by means of an electromotor which is thrown into circuit with a source of current-supply, such as a battery, by means of a relay connected with a track-circuit as the train passes to and from such circuit; and the object of my improvements is primarily to provide a coupling device between the motor and the actuating mechanism for the semaphore-arm whereby the motor will be disconnected therefrom at the instant the arm has been set, thereby allowing the motor to run free, the current for the motor being shut off at the same time and the motor being allowed to run down without sudden stoppage, as would otherwise be the case.

A further object is to provide a novel locking device connected with and actuated by the train-circuit, whereby the semaphore-arm will be held as set by the motor until the proper time for its release, the arm being returned to its other position when so released by means of a suitable counterweight or other means. Heretofore electromotors have been used in connection with semaphore-signals of this character, but there has been no means provided for uncoupling the motor from the actuating mechanism, lacking which the motor is brought to a sudden stop when the semaphore-arm has reached the end of its travel, resulting in injury to the motor and other running parts. By my arrangements of the several parts of my device I overcome this difficulty and also provide novel features whereby improved results are attained, as will hereinafter appear.

I attain my object by means of the construction and arrangement of parts as illustrated in the accompanying drawings, in which—

Figure 1 represents the top portion of a semaphore-mast and an end elevation of my

motor and intermediate mechanism as connected with a semaphore-arm; Fig. 2, a plan view of said mechanism; Fig. 3, a side elevation of the same showing in diagram the track-circuit and the several wire-circuits controlled by the relay; Fig. 4, a sectional detail of the clutch devices on line z z in Fig. 3; Figs. 5, 6, and 7, details showing the lock device, Fig. 5 being a section on line y y in Fig. 7, and Figs. 6 and 7 being sections of line z z in Fig. 7. Fig. 8 is a sectional detail showing the construction of the circuit-point on the relay connected with the magnet which actuates this locking device.

Like numerals designate like parts in the several views.

In the upper portion of Fig. 1 is shown the top of a semaphore-mast 1, in which the arm 2 is pivoted at 3, said arm being extended upon the opposite side of the pivot-shaft and provided with a weight sufficiently heavy to throw the arm into its elevated position when the arm is released from the motor-actuated shaft mechanism. The semaphore-arm is also provided with the usual colored bull's-eye for night signaling, a rim being located in the top of the mast for this purpose. Upon the shaft 3 is a drum from which a cord or chain passes to a drum on the shaft 5 of the shifting mechanism, whereby when said shaft is rotated from left to right the semaphore-arm will be drawn down and set at "safety," in which position it will remain until a train passes upon the track-circuit connected with this signal, when the lock device will be actuated to release the arm and allow it to be sprung up by its counterbalancing-weight to danger position—that is to say, the position assumed for the parts in Fig. 1—the arm being drawn down again and set at "safety" by the motor when the train has passed from the track-circuit.

To effect the drawing down of the semaphore-arm, the shaft 5 is coupled by a train of gears to the electromotor 10, the large gear 6 on shaft 5 meshing with a pinion on shaft 7, and gear 8, which is loosely mounted on shaft 7, meshing with a pinion on the shaft 9. Between the gear 8 and shaft 7 is a clutch device by which the motor is drawn into and out of gear with shaft 7 at the proper period to effect the setting of the semaphore-arm, as will hereinafter appear. This clutch con-

sists of a ring 27, positioned opposite the poles of a magnet 26, said ring being attached to a disk 28 and insulated therefrom by a ring 29, of fiber or other suitable material. The 5 disk 28 is provided with a hub 30, mounted loosely upon the hub of gear 8, upon which it is allowed more lateral play. Pins 31, projecting from the hub of gear 8, engage holes in disk 28, by which said disk is made to rotate with said gear. On the inner face of disk 28 is formed an annular series of V-shaped clutch-teeth 32, and a disk 33, fastened upon shaft 7, is provided with a similar series of teeth 34. Thus when the magnet 26 is energized 10 disk 28 will be drawn to the left in Fig. 4 until teeth 32 are in engagement with teeth 34, and the power of the magnet will be sufficient to hold these teeth in engagement, so that motion will be imparted to shaft 7 from the motor through gear 8. When the current is cut off from the magnet-coils, disk 28 will be pushed away from disk 33 by reason of the beveled clutch-teeth, and the motor will be uncoupled from shaft 7. In this 15 movement toward the magnet 26 the armature-ring 27 is not permitted to operate sufficiently to contact therewith, since if it were allowed to make contact the frictional resistance would be such as to impede or stop the motor. This armature is simply held within the magnetic field with sufficient power to retain the teeth 32 in contact with teeth 34 while the magnet 26 is energized and motion is being imparted through gear 8 to shaft 7. 20

25 While the stationary magnet will act to a certain extent as a brake upon the clutch-armature, which revolves within the magnetic field when the magnet is energized, the retardation of the motor and gear train resulting therefrom will not be appreciable by reason of the manner in which the gear-train is assembled. Moreover, this slight retardation will have a beneficial effect rather than otherwise, in that it will act as a governor 30 and will prevent the motor from racing.

35 The power for the motor 10 is supplied by a battery 11, the motor and battery being in circuit with relay 12, which in turn is in circuit with the rails 13 which form the section 40 of track controlled by the semaphore, a small battery 14 supplying the current for this track-circuit. The battery 11 and relay 12, together with the motor and shifting mechanism for the semaphore-arm, are located in 45 a suitable box or case at the foot of the mast 1, the motor and intermediate mechanisms being supported in bearings carried by a bracket or base, as illustrated in the drawings.

50 At 15 is a supplemental relay or magnet for actuating the lock device, and it is also in the track-circuit, as will be seen upon an examination of Fig. 3. From a binding-screw 55 on this relay a wire passes through binding-screw post 17 to a post 18 at relay 12, and from the

binding-screw 19 on relay 15 a wire passes through binding-post 20 to binding-screw 23 on motor 10, whence the circuit passes through the motor-coils to binding-screw 24 and thence through the battery 11 to binding-post 25 on relay 12. From binding-post 20 a second circuit is formed through the coils 21 of the magnet 26 by way of binding-post 22 and binding-screw 24 on the motor to battery 11. The coöperation of these several 70 magnet and motor circuits will be described hereinafter in connection with the complete operation of the mechanism.

75 The lock device by which the shaft 5 is held stationary after chain 4 has been wound onto the drum and the semaphore-arm set in its lowered position or at "safety," comprises a disk 35, secured upon shaft 5 and of the form shown more clearly in Fig. 5. This disk is provided with a pin 36 and has a notch 37, 80 cut in its rim in proximity to said pin. On the opposite side of the disk from this notch is a projection or stop 38, by which the throw of the disk from right to left is limited. In the standards 50 and 51 is journaled a shaft 85 43, the axis of which lies across the rim of disk 38, the shaft being cut in half between the standards, allowing the rim to move past it, as indicated at 44 in Figs. 5 and 6. On this shaft 43 is fastened a disk 42, from the 90 face of which a pin 41 projects into a slot in lever 39, which lever is pivoted upon the end of the shaft 40, supported in the standards 52 and 53. (See Figs. 5 and 6.) The free end of this lever 39 is positioned so as to be struck by pin 36 when disk 35 is rotated. Loosely journaled on shaft 43 between disk 42 and standard 50 is a second disk 47, from which extends a weight 48. From one face of this disk 47 projects a pin 46, which is engaged 95 by a notch in the periphery of disk 42, and from the other face of said disk 47 projects a pin 49, adapted to engage standard 50 to limit oscillation of said disk. On shaft 40 is fastened a grooved disk 54, provided at a 100 proper point in its periphery with a V-shaped tooth or projection 55, and passing around this disk is a stop 56, coupled at one end to pin 58 and at the other end coupled by a link 59 to lever 60, which lever is pivoted at 61 to 105 a bracket projecting from the supporting-frame of relay 15. The band 56 is provided with a socket at 57 to receive tooth 55 on disk 54 when the parts are thrown into the position shown in Fig. 7. These parts 54 and 56 have been shown in broken lines in 110 Figs. 5 and 7 in order that the other parts of the device may be shown more clearly.

115 The lever 60 carries at one end the armature-bar 69 and at the other end a contact-point 62, adapted to engage the contact 63, by which a circuit from binding-screw 19 to binding-screw 16 on relay 15 is made or broken at the proper periods in order to allow for the necessary play in lever 60, and to pro- 120 130

vide for proper contact between the points 62 and 63 I provide a novel construction whereby a limited motion of point 63 is permitted after it is engaged by contact 62; and 5 I also provide for setting this point or pin 63 so that it may be engaged at the proper time by contact 62. To accomplish this end, the pin 63 is housed in a hollow screw 66, which is screwed into a fiber or other non-conducting bushing 67, set in a standard rising from the frame of relay 15. The binding-screw or nut 19 is also screwed upon the hollow screw 66, so as to hold the socket-wire between said nut and bushing and in contact with the screw 66. A second hollow screw 64 is secured into screw 66, the rear end of pin 63 being adapted to slide in this hollow screw and a collar on pin 63, by which said collar is forced out against the end of screw 66 when 15 lever 60 is retracted. By means of screw 66 the pin 63 is set in proper position to be struck by contact 62 at the proper moment, and by means of screw 64 the tension of spring 65 may be adjusted.

20 25 The operation of the various parts of my device will be as follows: In the position in which the several parts are shown in Figs. 1 to 7 a train is assumed to be in the block protected by the signal and the semaphore is set 30 at "danger" or with the semaphore-arm at its elevated position. As soon as train has passed from the block the circuit between battery 14 and relay 12, which has been short-circuited while the train has been passing 35 over track 13, is again established, and the magnets in relays 12 and 15 will be again energized, by reason of which the armature of relay 12 will close the circuit between binding-posts 18 and 25, thereby establishing circuit between battery 11, motor 10, and magnet-coils 21. The circuit passes from binding-post 18 through binding-screws 16 and 19 of relay 15, and thence through binding-post 20 to the motor-coils, thence to battery 40 45 11, binding-post 25, and through the relay armature back to post 18. The circuit through binding-screws 16 and 19 is established through contacts 62 and 63 and lever 60, which lever is held in the position shown in 50 55 Fig. 5 by reason of the position of the tooth 55 on disk 54, which holds bands 56 away from the rim of said disk, thereby preventing armature 69 from being drawn to the magnet on relay 15, which magnet is energized by the track-circuit passing through the relay-coils. As the circuit is now also passing through coils 21 of magnet 26 the clutch-disk 28 will be brought into engagement with disk 33, and the motor, by means of gears 8 and 6, 60 65 will impart motion to shaft 5, thereby winding chain 4 upon the drum of said shaft and drawing the semaphore-arm down into its depressed or safety position. As the shaft 5 is being rotated to wind chain 4 upon the drum, disk 35 will be turned until pin 36

strikes the lever 39, after which the further rotation of said disk will cause said lever, by reason of the pin-and-slot connection 41, to impart motion to disk 42, thereby causing the halved shaft 44 to be turned into notch 37. At the same time disk 42 will engage the pin 46 on disk 47, so as to throw the weight 48 into its elevated position, the pin 49 on disk 47 engaging the standard 50 to limit the throw of the said weight, the parts then assuming the positions shown in Fig. 7. As the lever 39 is thrown down by pin 36 it also imparts motion to disk 54 through shaft 40, causing tooth 55 to be moved into alignment with socket 57 on band 56. As soon as tooth 55 comes into register with said socket 57 the band 56 will be thrown in against the rim of disk 54 by armature 69, which is then free to be acted upon by the magnet of relay 15. This motion of the armature 69 throws the lever 60 into its retracted position, thereby throwing contacts 62 and 63 out of contact and breaking the circuit from battery 11 through relay 12, magnet-coils 21, and motor 10. This demagnetizes magnet 26 and releases clutch-disk 28, thereby disconnecting the motor from shaft 7 and the semaphore-drum. The current at the same instant is shut off from the motor, but the motor will continue to run for some little time after, owing to its momentum. As the clutch is released, however, at the same instant that the current for the motor is shut off, the motor will be left free to run down without having been brought to a sudden stop when the semaphore-arm has reached the end of its travel. The lock device has now assumed the position shown in Fig. 7, and it will remain in this position until the track-circuit is again short-circuited by a train passing over it. Disk 35, however, will be allowed a small backward motion until the lower end of slot 37 in Fig. 7 contacts with shaft 44, after which the shaft 5 will be held locked with the semaphore-arm elevated until the magnets or relays 15 are demagnetized by the short-circuiting of battery 14. When this takes place—that is to say, when a train passes into the block—the armature 69 will be released, thereby allowing tooth 55 on disk 54 to be forced out of socket 57 on band 56, because of weight 48 acting through pin 46, disk 42, pin 41, and arm 39 to turn disk 54 from left to right in Fig. 7, so as to return said disk to the position shown in Fig. 5. As disk 42 is turned by the action of the weight 48 it will turn shaft 44 out of engagement with notch 37, thereby releasing disk 35 and allowing the counterweight on the semaphore-arm to throw said arm up, shaft 5 and gears 6 and 8 being given a backward turn sufficient to permit the unwinding of chain 4 from the drum of said shaft. The notch on disk 42 is elongated in order to allow for the play of weight 48 after shaft 44 has assumed the position shown in Fig. 7.

tion shown in Fig. 5. Otherwise said shaft would be turned against the rim of disk 35, so as to pinch said rim and prevent the disk from rotating. The movement of disk 35 from right to left is limited by reason of the stop 38 coming against shaft 44, thereby preventing the further unwinding of chain 4 from the drum on shaft 5 and limiting the movement of the semaphore-arm in this direction. By the release of armature 69 the lever 60 is thrown so as to bring point 62 and pin 63 again into contact, and the circuit between binding-screws 16 and 19 is re-established. As relay 12 has been also short-circuited from battery 14 the circuit between binding-posts 18 and 25 is broken, and the motor is therefore cut out from battery 11. All parts have therefore been returned to the position assumed for them in Figs. 1 to 6, inclusive, and will so remain until the train has passed from the block, after which the operation of the several parts will be repeated to set the semaphore at its safety position.

While I have described a particular form of locking device in connection with my improvements, I do not desire to be limited to this specific form of this device in combination therewith, nor do I desire to be limited to the specific form of clutch device shown for throwing the motor into and out of connection with the drum-shaft. Other details may also be varied without departing from the spirit of my invention.

Having thus described my improvements, what I claim as my invention, and desire to secure by Letters Patent, is—

1. In a railway block-signal, the combination with a semaphore-arm and its actuating mechanism, of an electromotor to impart motion to said mechanism in one direction, independent means for reversing said mechanism, a coupling device between the motor and said mechanism, an electromagnet to actuate said coupling device, a lock device to hold the semaphore in position when the motor is uncoupled, an electromagnet controlling said device, a track circuit and relay controlling said motor-circuit, the lock-magnet being included with the relay in the track-circuit and the coupling-magnet being included in the motor-circuit, and means actuated by the locking-magnet for opening and closing the motor-circuit.

2. In a railway block-signal, the combination of a pivotal semaphore-arm, connection therefrom to an actuating-shaft, an electromagnet, a train of gears between said motor and shaft, one of said gears being loosely mounted on its shaft, a coupling device between said gear and its shaft, an electromagnet included in the motor-circuit to actuate said coupling device, a locking device to hold the shaft when the semaphore has been set, an electromagnet controlling said locking device, a circuit-breaker actuated thereby to

cut out the motor and the coupling-magnet when the lock is set, a relay controlling the magnet-circuit, a track-circuit including the relay and the locking-magnet, and means for resetting the semaphore-arm when the lock is released.

3. In a railway block-signal, the combination of a pivotal semaphore-arm, a counter-weight to move said arm in one direction, a drum on an actuating-shaft and connected with said arm to move it in the other direction, an electromotor, a train of gears between said motor and shaft, one of said gears being loosely mounted on its shaft, a coupling device between said gears and its shaft, an electromagnet included in a motor-circuit to actuate said coupling device, a lock device to hold the drum-shaft when it has moved the semaphore-arm into position, an electromagnet controlling said locking device, a circuit-breaker actuated thereby to cut out the motor and the coupling-magnet when the lock is set, a relay controlling the circuit for the motor and coupling-magnet, and a track-circuit including the relay and the locking-magnet.

4. In an electrically-operated semaphore, the combination, with the actuating mechanism, of an electromotor, a train of gears whereby motion is imparted from one to the other, one of said gears being loosely mounted on its shaft, a longitudinally-movable member, of a coupling device carried by said gear, a fixed member revolving with the shaft of said gear, coupling-teeth carried by said members, a stationary electromagnet included in the motor-circuit, whereby the movable member is drawn into engagement with the fixed member of the coupling device when the motor-circuit is closed, means for locking the actuating mechanism when the semaphore has been set, an electromagnet controlling said locking means, a circuit-breaker actuated thereby to cut out the motor and coupling-magnet when the lock is set, a relay controlling the motor and coupling-magnet and a track-circuit including the relay and locking magnet.

5. In an electrically-operated semaphore, the combination, with the actuating mechanism, of a driving-shaft therefor, a gear carried on said shaft, a second shaft carrying a pinion meshing with said gear, a gear loosely mounted upon said second shaft, a coupling device between said gear and shaft, a stationary electromagnet for actuating the movable member, the said coupling device, electromagnet, and pinion on the shaft meshing with said loose gear, said motor and magnet being included in the same circuit, means for locking the actuating mechanism when the semaphore has been set, an electromagnet controlling said locking means, a circuit-breaker actuated thereby to cut out the motor and coupling-magnet when the lock is set.

a relay controlling the motor and coupling-magnet, and a track-circuit including the relay and locking-magnet.

6. In an electrically-operated semaphore, 5 the combination with the actuating-shaft, of a locking device therefor comprising a disk fixed upon said shaft, a pin projecting from one side thereof, a notch in the periphery of the disk in proximity to said pin, a shaft having a cut-away section lying against the periphery of the disk, a lever adapted to turn said shaft into said notch when struck by said pin, and means for retaining said shaft in such position until the actuating-shaft is 15 to be released.

7. In an electrically-operated semaphore, the combination, with the actuating-shaft, of 20 a locking device therefor, comprising a disk fixed upon said shaft, a pin projecting from one side of said disk, a notch in the periphery of the disk in proximity to said pin, a shaft having a cut-away section lying against the periphery of the disk, a lever adapted to turn said shaft into said notch when struck by 25 said pin, a disk fixed upon the pivot-shaft of said lever, a hinged strap passing around said disk, an interlocking connection between said disk and strap when the lever is thrown, an electromagnet and its armature, the free end 30 of said strap being coupled to said armature to effect said connection, and a weight to return the parts to place when the current is cut off from said magnet.

8. In an electrically-operated semaphore, 35 the combination, with the actuating-shaft, of

a locking device therefor comprising a disk fixed upon said shaft, a pin projecting from one side of said disk, a notch in the periphery of the disk in proximity to said pin, a shaft having a cut-away section lying against the 40 periphery of the disk, a second disk attached to one end of said shaft, a lever pivoted adjacent said disk having a pin-and-slot connection therewith, the free end of said lever being in position to be struck by the pin on the 45 first-named disk, a weighted arm loosely mounted at the side of the second disk, a pin projecting therefrom into an elongated notch in the periphery of said disk, and means actuated by the electromagnet for locking and 50 releasing said lever at the proper periods.

9. In an electrically-operated semaphore, the combination, with the actuating-shaft, and an electric motor for imparting motion thereto, of a track-circuit and relay controlling the motor-circuit, a locking device for 55 said actuating-shaft, an electromagnet in the track-circuit having its armature for operative connection with said locking device, a lever carrying said armature at one end and 60 provided with a contact-point at its other end, and a contact in position to be engaged thereby, said lever and pin being included in the motor-circuit, whereby said circuit will be broken when the lock is set.

HARRY M. ABERNETHY.
